CHAIN BED MOTION FOR PRINTING PRESSES

William M. Kelly, Westfield, N. J.

Application August 24, 1942, Serial No. 456,099

6 Claims. (Cl. 101—282)

This invention relates to printing presses of the flat-bed type, wherein the bed is reciprocated back and forth beneath the impression cylinder of the press. More particularly, the invention relates to a bed motion employing a horizontally arranged endless driving medium with a link or similar member coupling one part of said endless driver with the bed to provide a constant feed of the bed back and forth in the press, and especially in providing a uniform speed of the bed during the printing stroke of the press. The novel features of the invention will be best understood from the following description when taken together with the accompanying drawings, in which certain embodiments of the invention are disclosed, and in which the separate parts are designated by suitable reference characters in each of the views; and in which:

Fig. 1 is a diagrammatic longitudinal sectional view through a printing press made according to my invention.

Fig. 2 is a cross sectional view substantially on the line 2—2 of Fig. 1, also diagrammatically illustrating the invention, and

Fig. 3 is a partial sectional plan view substantially on the line 3—3 of Fig. 1 and omitting parts of the construction.

In the operation of printing presses of the type and kind under construction, many types and kinds of bed motions have been employed, and most of these motions have involved the intermittent pick-up and carry motion. Efforts have also been made to provide what might be termed a chain drive, employing vertically arranged sprockets and chains with the coupling between the chain and bed moving vertically with respect to the plane of the bed. Such latter structures have involved complicated mechanisms and materially interfere with the proper arrangement of various press structures, such for example, as air cylinders and the like. The "hanger" or slotted yoke in this construction adds considerable weight to the reciprocating bed.

It is the purpose of my invention to provide a simple, practical and economical bed motion, employing an endless driver which is disposed horizontally, or substantially so, beneath the bed with means in the form of a link for coupling the driver with the bed in such manner as to centralize the transmission of power to the bed in actuating the same, while at the same time employing a full bed motion with a minimum length of conveyor driver. Further, a bed motion of this type and kind, also materially simplifies the drive between the bed and the impression cylinder and maintains the means for properly

supporting the bed and accommodating conventional press parts or mechanisms, within the normal limits of the press frame.

In the accompanying drawings the press structure generally is diagrammatically illustrated and the reference 10 indicates the general press frame upon the top portion of which are arranged bed tracks 11, in which rollers 12, of the bed 13 operate. On the surface of the bed 13, is indicated 10 a type form 14.

Centrally of the frame is a drive shaft 15 having at one end a large gear 16 which meshes with an idler 17, the latter in turn meshing with a gear 18, on the shaft of the impression cylinder 19. Arranged adjacent the cylinder 19, are ink rollers 20, and in Fig. 1 I have shown at 21, part of a feed board adjacent the cylinder 19.

It will be noted from a consideration of Fig. 2 of the drawings that the tracks 11 are disposed 20 centrally of the bed, as well as at side portions thereof. This provides a well supported bed, and also does not interfere with the air cylinders 22, usually employed within the frame of the press as is diagrammatically illustrated in Fig. 2. The 25 foregoing brief description generally outlines at least part of one form of press construction however, it will be understood that my invention is applicable to any type and kind of press construction in which the bed motion herein later 30 described can be practically employed.

Disposed between the centrally arranged tracks 11 is a bed connecting bracket and gib 23, with which is coupled pin 24, note Fig. 1, and to this pin is coupled one end of a coupling link 25, the 35 other end of which is coupled with a pin 26 secured to a chain or other conveyor 27. The chain or conveyor passes around two guide members or sprockets 28 and 29 suitably supported within the frame of the press and if desirable 40 the sprocket 29 may be adjustable toward and from the sprocket 28, and may comprise a toothless idler.

The sprocket 28 is arranged upon a shaft 30 45 on which is also secured a bevel gear 31, which meshes with a bevel gear 32, on the shaft 15, as clearly seen in Fig. 2 of the drawings.

It will appear that when the bed is at one end 50 of the press as indicated in Fig. 1 of the drawings, the coupling link 25 extends between the central outer end portion of the bed and the corresponding center of the driver 27. As the press operates the rotation of the chain or conveyor driver will move the bed back and forth in the 55 frame of the press in each cycle of operation of the press, and during this operation the cou-

pling pin 26, will have returned to the position shown in Figs. 1 and 3. In the above operation, it will be apparent that the pin 26 follows the path of the endless driver 27, whereas the pin 24 maintains its centralized position, or in other words, is not shifted relatively to the bed; further, the link maintains a definite plane of operation which will be parallel or substantially parallel to the movement of the bed. It may be said that the link 25 comprises a connecting rod interposed between the bed, which constitutes the driven member, and the driver which constitutes the endless chain.

It will be apparent that suitable means may be provided to house, support and guide the endless chain or driver around and intermediate the sprockets and such means will facilitate lubrication of the driver; however, in that the present illustration is purely diagrammatic, this and other structural details have been omitted to simplify the disclosure. The reciprocating parts of my present press design weigh considerably less than any known flat-bed design. By reason of this fact, the press may be operated safely at high speed, a much sought factor in modern press design.

The bed travel is uniform and synchronous with cylinder speed during the travel of the pin 26 between sprocket centers.

Having fully described my invention, what I claim as new and desire to secure by Letters Patent is:

1. In a flat-bed printing press, the combination with a bed mounted for reciprocating movement back and forth in the press frame and with respect to an impression cylinder arranged centrally of the frame, of means imparting reciprocating movement to said bed, said means comprising two sprockets spaced centrally and longitudinally of the path of movement of the bed and having axes arranged perpendicularly to the bed, an endless chain engaging said spaced sprockets, a connecting member movably coupled with the bed and with one portion of the chain whereby in each cycle of operation of the chain, said bed is reciprocated back and forth in the press frame and with respect to said impression cylinder means for driving at least one of said sprockets, and said member comprising a connecting rod pivoted to the bed centrally of one end portion thereof.

2. In a flat-bed printing press, the combination with a bed mounted for reciprocating movement back and forth in the press frame and with respect to an impression cylinder arranged centrally of the frame, of means imparting reciprocating movement to said bed, said means comprising two sprockets spaced centrally and longitudinally of the path of movement of the bed and having axes arranged perpendicularly to the bed, an endless chain engaging said spaced sprockets, a connecting member movably coupled with the bed and with one portion of the chain whereby in each cycle of operation of the chain, said bed is reciprocated back and forth in the press frame and with respect to said impression cylinder, means for driving at least one of said sprockets, said driving sprocket being arranged substantially centrally of the press, the other sprocket being arranged at one end of the press and said member projecting from the chain in the direction of the other end of the press and being coupled with the corresponding end portion of the bed substantially centrally thereof.

3. In a flat-bed printing press, the combination with a bed mounted for reciprocating movement back and forth in the press frame and with respect to an impression cylinder arranged centrally of the frame, of means imparting reciprocating movement to said bed, said means comprising two sprockets spaced centrally and longitudinally of the path of movement of the bed and having axes arranged perpendicularly to the bed, an endless chain engaging said sprockets, a connecting member movably coupled with the bed and coupled with said chain to operate back and forth beneath said cylinder within the ends of said cylinder in each cycle of operation of the chain, said member reciprocating said bed back and forth in the press frame and with respect to said impression cylinder, and means for driving at least one of said sprockets.

4. In a flat-bed printing press, the combination with a bed mounted for reciprocating movement back and forth in the press frame and with respect to an impression cylinder arranged centrally of the frame, of means imparting reciprocating movement to said bed, said means comprising two sprockets spaced centrally and longitudinally of the path of movement of the bed and having axes arranged perpendicularly to the bed, an endless chain engaging said sprockets, a connecting member movably coupled with the bed and coupled with said chain to operate back and forth beneath said cylinder within the ends of said cylinder in each cycle of operation of the chain, said member reciprocating said bed back and forth in the press frame and with respect to said impression cylinder, and means for driving at least one of said sprockets, said last named means comprising a bevel gear on a drive shaft of the press engaging a bevel gear on the sprocket shaft, and a gear train placing the drive shaft in operative engagement with said impression cylinder.

5. A bed motion for flat-bed printing presses employing an impression cylinder and a bed mounted for reciprocation back and forth with respect to said cylinder, comprising an endless driver, two members spaced longitudinally of the press for supporting and guiding the driver to operate in its entirety horizontally and substantially parallel to and beneath the path of movement of the bed, means on the driver and movably coupled with said bed to reciprocate the bed back and forth beneath said cylinder in each cycle of operation of the driver, and means in operative engagement with a drive shaft of the press for actuating one of said members to operate said driver.

6. A bed motion for flat-bed printing presses employing an impression cylinder and a bed mounted for reciprocation back and forth with respect to said cylinder, comprising an endless driver, two members spaced longitudinally of the press for supporting and guiding the driver to operate in its entirety horizontally and substantially parallel to and beneath the path of movement of the bed, means on the driver and movably coupled with said bed to reciprocate the bed back and forth beneath said cylinder in each cycle of operation of the driver, means in operative engagement with a drive shaft of the press for actuating one of said members to operate said driver, and said first named means having a swingable coupling with the bed and being disposed and operated between the lower surface of the bed and the upper surface of said driver.

WILLIAM M. KELLY.
